(57) **CLAIM**

The ornamental design for an industrial model attachment for animal feeding, as shown and described.

DESCRIPTION

FIG. 1 is a top right perspective view of an industrial model attachment for animal feeding of my invention;

FIG. 2 is a right side view of the industrial model attachment for animal feeding of FIG. 1;

FIG. 3 is a left side view of the industrial model attachment for animal feeding of FIG. 1;

FIG. 4 is a front view of the industrial model attachment for animal feeding of FIG. 1;

FIG. 5 is a rear view of the industrial model attachment for animal feeding of FIG. 1;

FIG. 6 is a top view of the industrial model attachment for animal feeding of FIG. 1;

FIG. 7 is a bottom view of the industrial model attachment for animal feeding of FIG. 1; and,

FIG. 8 is the top right perspective view of the industrial model attachment for animal feeding shown in an environmental view.

The portions shown in broken lines form no part of the claimed design.

1 Claim, 6 Drawing Sheets
